Primary Examiner — Clint A Samuel

(57) **CLAIM**

The ornamental design for floor lamp, as shown and described.

DESCRIPTION

FIG. 1 is a front perspective view of floor lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its state diagram thereof;

FIG. 10 is its state diagram thereof; and,

FIG. 11 is an enlarged detail view of area 11 in FIG. 1. The long dash-short dash broken lines in FIGS. 1 and 11 show the boundaries of the enlargements shown in FIG. 11, and form no part of the claimed design.

1 Claim, 11 Drawing Sheets11
